UNITED STATES PATENT OFFICE.

RUDOLF LOEB, OF JENKINTOWN, PENNSYLVANIA.

EMBROIDERY ORNAMENTATION AND PROCESS OF MAKING THE SAME.

1,262,071.

Specification of Letters Patent.

Patented Apr. 9, 1918.

Application filed July 31, 1916. Serial No. 112,364.

To all whom it may concern:

Be it known that I, RUDOLF LOEB, a citizen of the United States, and a resident of Jenkintown, Montgomery county, Pennsylvania, have invented certain Improvements in Embroidery Ornamentation and Processes of Making the Same, of which the following is a specification.

My invention relates to embroidered fabrics, and it consists of an ornamental eyelet-stitched and corded edge for fabrics produced by suitable stitch-laying means including a vibrating needle which, in addition to vibratory movement to lay the 15 stitches, is rotatable as a whole about a predetermined center or centers so as to lay stitches radially with respect to said center (or centers) and form eyelets, relatively circular, or of other shape, at the edge of the 20 fabric continuous with the stitches of straight portions of the embroidery at the edge or margin of the fabric between said eyelets.

The eyelets may be circular or as nearly 25 circular as it is possible for a machine to effect such stitching, or of other shape, and such eyelets may be disposed outside the marginal edge of the body of the fabric and connected thereto, or within the body 30 of the fabric inside the margin or edge of the same; such margin or edge in each instance being composed of stitches continuous with the eyelets. Or the eyelets may be relatively oval in shape or contour, and the 35 stitching thereof may be continuous with curved portions or sections of the marginal embroidered edge of the fabric.

The stitches formed are in the nature of overedging stitches, produced by a thread 40 laid by a vibrating needle in conjunction with a shuttle thread; the two threads being locked at the outer edge of the stitches in the marginal or edge portion of the fabric, and on the inner marginal edge of the 45 eyelets, whether circular, oval or of other shape or contour.

When forming the relatively circular eyelets at the margin of a piece of fabric; inside or outside the same, and between the 50 rotative movements of the stitch laying means, during which time the radially disposed stitches are formed, the fabric is given a longitudinal movement, which may be of any desired length, usually predetermined, so that between the circular eyelets, substantially straight stitched portions for

the edge of the fabric will be formed. When forming the oval eyelets between which curved sections of the margin or edge of the fabric are disposed, the fabric will be 60 given a double movement; that is to say, it will be fed forward simultaneously with a lateral movement in two directions; the resultant of such feeding movements being a curved edge between the oval eyelets made 65 up of stitching continuous with that forming said oval eyelets.

As in the operation of overedging machines of the usual type, means may be provided whereby the fabric may be cut ahead 70 of the stitching operation in a straight line; or in any desired curvature depending upon the ornamentation desired, or the cutting step may be omitted and the stitching may be directly applied to the edge of a fabric 75 which may be in one or more plies, or to the body of the fabric. The stitches formed may be of the overedge or buttonhole type, and consist of a series of loops laid in zigzag fashion around the cord or over the edge 80 of the fabric and locked on a marginal edge of the same by the shuttle thread.

These and other features of my invention will be more fully described hereinafter, reference being had to the accompanying 85 drawing, more or less diagrammatic in character, in which:

Figure 1, is a view of one form of embroidered edging within the scope of my invention, in which the eyelets are formed outside 90 or beyond the margin or edge of the fabric.

Fig. 2, is a similar view of another form of embroidered edging in which the eyelets are formed within the body of the fabric 95 at the edge or margin of the same.

Fig. 3, is a similar view of another form of embroidered edging in which the eyelets are relatively or substantially oval and are formed within the body of the fabric adjacent the edge or margin of the same which is curved in outline or contour between said eyelets.

Fig. 4 illustrates the manner in which embroidery edging forming the subject of my 105 invention of the type illustrated in Fig. 1, is commenced.

Fig. 5, illustrates the manner in which the stitches of the edging shown in Fig. 1, are laid when the needle is rotated with respect to the fabric in the formation of the 110 eyelets.

Figs. 6, 7 and 8, show successive stages in the formation of the embroidered edge shown in Fig. 1, and

Figs. 9 and 10, are perspective views of the needle and co-operating members constituting the stitch-laying means; Fig. 10, showing the eyelet-forming member in the raised position.

One form of the embroidery ornamentation forming the subject of my invention and shown in Figs. 1, 4, 5, *et seq.*, may comprise a series of connected eyelets 1 applied to and extending beyond the edge of a fabric 2; such eyelets being composed of a plurality of stitches 3 formed by a needle thread and a shuttle thread, which stitches are locked at the points indicated at 4. The stitches overlie or surround a cord 5 which is suitably fed to one of the members of the stitch-laying means, whereby said cord may be laid adjacent the edge 2^a of the fabric simultaneously with the stitching operation and just in advance of the movements of the needle. The stitch-laying mechanism is so controlled that the stitches, the needle thread portions of which are laid by a vibrating needle 7, first stitch a portion of the edge of the fabric, which edge may be cut in advance of the stitching or not, as desired, such stitching extending to a point which may be predetermined as the center of an eyelet to be formed adjacent to and connected with said stitched edge. When this point is reached, the stitch laying mechanism is rotated with respect to the fabric which remains stationary; a suitable member 8 rotating with the other parts being lowered by suitable means (not shown) at this stage of the operation and around which the cord over which the stitches are formed is laid to provide the desired eyelet ornamentation. This member 8 is open at one side, as at 9, so that the needle can work in and out of the same and lay the stitches over the cord as it is fed to the rotating member and the vibrating needle.

The needle 7 and the member 8, in forming the embroidery shown in Fig. 1, are rotated a full circle, bringing the needle back to the point at which it started to form said eyelet, and then the fabric is moved forward by a suitable feeding presser foot 10, which may be actuated in the usual manner to the desired extent; the overedge stitches being formed during such movement until the predetermined center of the next eyelet is reached. The fabric is then stopped, and the rotation of the needle with respect to the same is again effected; forming a second eyelet, the stitches being laid over the cord in the same manner as before, and so on until the complete and fully embroidered edge is formed.

The needle operates within a stitching member 11 which is revolved by suitable

means, and within which is mounted the member 8 around which the cord is laid while the needle operates to overlay the same with stitches which are locked by the shuttle thread; said cord entering said stitching member 11 at the opening 12 and being delivered thereby to the straight and curved portions of the embroidery ornamentation. The member 8 is raised when the straight portion of the stitching takes place, but is lowered when it is to be rotated with the other stitch member so that the needle may vibrate with respect to the same and lay the stitches over or around the cord wound around said member 8. The operation of the mechanism controlling the needle and other members of the stitch-laying mechanism is wholly automatic; changing from straight stitching at which time the fabric is fed forward by the usual presser foot, to round or curved stitching when the fabric is held stationary and the feeding presser foot is lifted, and then back to straight stitching, and so on.

While I have shown in Figs. 1, 4, 5, 6, 7 and 8, the application of the embroidered eyelet as projecting beyond the edge of the fabric, it will be understood that this arrangement can be reversed, and that the edge of the fabric may be provided with the straight or relatively straight stitched portion of the embroidered edge, with the eyelet portions inwardly disposed with respect to the fabric, substantially as illustrated in Figs. 2 and 3.

In Fig. 2, the eyelets are of the truly circular type, such as illustrated in Figs. 6, 7 and 8, and the marginal edge or the embroidery is substantially straight. In the form shown in Fig. 3, however, the stitching is effected in a series of curves forming a scallop or indented edge, with eyelets formed in the body of the fabric at the root of the indentation; the marginal edge of the fabric and the borders of the eyelets being formed continuously in the same manner as in the structure illustrated in Figs. 1, 4, 5, 6, 7 and 8.

The oval or relatively oval eyelets with the curved edge sections between the same are produced by the use of cams designed to move the fabric in relation to the stitch-forming means so that the eyelets will be formed while the stitch members are rotating, while the curved sections of the edge between such oval eyelets will be developed by feed movement imparted by the presser foot in two directions; that is to say, lateral movement in both directions will be imparted to the fabric as it is moved forward by the presser foot, and the resultant of these movements while stitching is being effected will be curved portions between the eyelets. If desired, this compound feed may be effected in connection with the for-

mation of round eyelets, as well as with the oval eyelets.

While I have described my invention as being employed with the fabric in which the edge is trimmed ahead of the embroidery operation, such ornamentation is not limited to application to such an edge, and it can, in fact, be applied to any fabric edge whether preformed or not.

10 I claim:

1. As a new article of manufacture, an edging for fabrics comprising a plurality of eyelets disposed at the edge of said fabric, said eyelets being formed of radial stitches,

15 overedging stitches at the edge of the fabric continuous with the eyelet-forming stitches and between the same and a continuous cord inclosed by the several stitches.

2. As a new article of manufacture, an edging for fabrics comprising a plurality of eyelets projecting beyond the edge of said fabric, said eyelets being formed of radial stitches, and overedging stitches at the edge of the fabric continuous with the eyelet forming stitches and between the same and a continuous cord inclosed by the several

25 stitches.

3. As a new article of manufacture, an edging for fabrics comprising a plurality of eyelets disposed at the edge of said fabric, said eyelets formed of radial stitches overlying and inclosing a central core or cord and connected continuously with the edge of the fabric.

35 4. As a new article of manufacture, an edging for fabrics comprising a plurality of eyelets projecting beyond the edge of said fabric, said eyelets formed of radial stitches overlying and inclosing a central core or cord and connected continuously with the edge of the fabric.

5. As a new article of manufacture, an edging for fabrics comprising a plurality of eyelets disposed at the edge of said fab-

45 ric, said eyelets formed of radial stitches overlying and inclosing a central core or cord, and overedged stitches at the edge of the fabric between said eyelets.

50 6. As a new article of manufacture, an edging for fabrics comprising a plurality of eyelets disposed at the edge of said fabric, said eyelets formed of radial stitches overlying and inclosing a central core or cord, and overedged stitches at the edge of the fabric between the eyelet portions; said overedged stitches being continuous with the eyelet forming stitches and formed over the same cord constituting the core of said eyelet forming stitches.

60 7. The process of forming embroidery

edging, which consists in forming stitches with respect to the edge of a fabric by means including a stitch-laying element, simultaneously applying a cord to said fabric over or around which said stitches are laid, 65 moving the fabric at intervals, and moving the stitch-laying implement during the periods of rest of said fabric whereby rows of stitches are formed over the cord during said intervals and following a path differing 70 from that of the stitches formed while the fabric is moving, all of said stitches covering the cord and the latter constituting a core.

8. The process of forming embroidery 75 edging, which consists in forming stitches with respect to the edge of a fabric by means including a stitch-laying element, simultaneously applying a cord to said fabric over or around which said stitches are laid, 80 moving the fabric at intervals, and rotating the stitch-laying implement during the periods of rest of said fabric whereby circular rows of stitches are formed over the cord during said intervals; all of said 85 stitches covering the cord and the latter constituting a core.

9. The process of forming embroidery edging, which consists in forming stitches with respect to a fabric by means including 90 a stitch-laying element, simultaneously applying a cord to said fabric over or around which said stitches are laid, moving the fabric at intervals, moving the stitch-laying implement during the periods of rest of said 95 fabric, and laying the cord in a path following the movement of the stitch laying element and its simultaneous vibrations whereby rows of stitches are formed over the cord during said intervals and following a path 100 differing from that of the stitches formed while the fabric is moving to form an eyelet; all of said stitches covering the cord and the latter constituting a core.

10. The process of forming embroidery 105 edging, which consists in forming stitches with respect to a fabric by means including a stitch-laying element, simultaneously applying a cord to said fabric over or around which said stitches are laid, moving the 110 fabric at intervals, rotating the stitch-laying implement during the periods of rest of said fabric, and laying the cord in a circular path during the rotation of the stitch laying element and its simultaneous vibrations 115 whereby circular rows of stitches are formed over the cord during said intervals; all of said stitches covering the cord and the latter constituting a core.

RUDOLF LOEB.
